STOKER

Filed April 7, 1924

Inventor
Allen G. Barkhie,
George Heidman
Attorney

UNITED STATES PATENT OFFICE.

ALLEN G. BARKHIE, OF CHICAGO, ILLINOIS.

STOKER.

Application filed April 7, 1924. Serial No. 704,589.

To all whom it may concern:

Be it known that I, ALLEN G. BARKHIE, a citizen of the United States, and a resident of Chicago, in the county of Cook and State 5 of Illinois, have invented certain new and useful Improvements in Stokers, of which the following is a description, reference being had to the accompanying drawing, which forms a part of my specification.

10 My invention relates to stokers for stationary boilers, or for marine boilers which are usually arranged side by side; the invention relating more especially to an over-feed stoker whereby a battery of boilers may 15 be simultaneously supplied with fuel, delivered into the firebox at a point above the grates of the boilers.

One object of my invention is to provide 20 stoker mechanism whereby the fuel will be automatically delivered in a substantially even or uniform manner throughout the firebox of the boilers, namely throughout the entire grate bar area of the firebox from front to rear of the firebox and uniform combustion maintained.

25 The objects and advantages of my invention will be more fully comprehended from the following detailed description of the accompanying drawing, wherein:—

30 Figure 1 is a sectional elevation of a portion of the firebox of a boiler provided with my improved stoker mechanism which is shown in elevation.

Figure 2 is a detail sectional view, in perspective, of the fuel carrying and feeding portion of the stoker.

35 Figure 3 is a detail sectional view taken substantially on the line 3—3 of Figure 1 looking in the direction of the arrows.

40 Figure 4 is a detail view in side elevation of the fuel carrying and feed mechanism shown in Figure 2, showing the opposite side thereof.

45 In the particular exemplification of the invention, a portion of the firebox end of a boiler is illustrated at 10, with a portion of the inner wall shown at 11 and the outer wall shown at 12; the firebox being provided with any suitable grate construction as illus-

50 trated at 13. The outer wall 12 is provided with the usual firedoor at 14 at a point slightly above the plane of the grate-bars and this wall at a point above the usual firedoor 14 is provided with a door 15 extending

substantially throughout the width of the 55 firebox. The door 15 is mounted to slide vertically into and out of closed position and is shown controlled by means of a suitable cable or chain 16 disposed about a pulley 17 secured to the wall of the firebox; the 60 cable or chain extending to a suitable point where it may be controlled by any suitable mechanism common to all doors 15 of each boiler of the battery, in order that these doors may be simultaneously controlled. 65

At a point removed from the outer wall of the firebox, I provide a suitable supporting frame, composed of standards as at 18, which may be provided with an electric motor as at 19, with the armature-shaft 70 thereof provided with a belt or chain 20. This belt 20 extends about a pulley 21 secured to the end of a shaft 22 which has proper bearing in the upper part of the standards of the supporting frame 18 and 75 which shaft extends transversely of the entire battery of boilers; a method of supporting the shaft being more clearly shown in Figure 3.

The shaft 22, at points substantially in alignment with the center of each door opening 15, is provided with a cog-wheel 23 arranged in mesh with a rack bar 24, which is of length sufficient to extend practically to the inner wall 11 of the firebox and still 85 remain in mesh with the cog-wheel.

The rack bar 24 may be of the inverted somewhat T-shape construction shown in Figure 3, for a major portion of its length; with the upstanding portion being provided 90 with the teeth with which the cog-wheel is in mesh. The lower laterally disposed portions of the rack-bar are arranged to travel between the lower roller 25 and the upper pair of rollers 26 disposed on each side of 95 the upstanding toothed portion of the bar; the rollers being suitably mounted in the supporting frame 18 and preferably in sets located both at the front and rear sides of the frame in order to provide suitable bearing for the rack-bar and at the same time permit easy longitudinal movement of the bar. 100

One end of this rack-bar is provided with a non-toothed portion as shown at 27, to 105 which the fuel feeding member or container 28 is securely fastened.

The fuel feeding container 28 is intended

to be of length substantially equal to the door opening 15 and therefore substantially equal to the width of the firebox; the container 28 being preferably provided with 5 an arcuate bottom 29, shown riveted to the bar 27 and also provided with end walls 30, 31 to provide a sector-shaped container. The container is also provided with side walls 32 and 33 pivotally secured to the 10 end walls as at 34 and 35, respectively; that is to say the side wall 32 is pivoted and disposed within the end walls 30 and 31, to permit the side wall 32 to swing within the container from its normal position shown 15 in full lines in Figure 2, to the dotted line position shown in said figure; while side wall 33 is arranged to lap or abut against the end walls and is therefore pivoted to the end wall exterior. The side wall 33 is intended 20 to swing outwardly away from the side of the container when the latter is traveling through the firebox opening 15.

The pivotal points 34 and 35 are spaced apart to provide the container 28 with an 25 opening in the top through which the fuel is introduced by means of a suitable chute 36 leading from an overhead hopper as illustrated; a portion of the hopper being shown at 37 in Figure 1. The chute 36, it will be 30 understood, may be of width and length to correspond with the width and length of the opening in the top of each container, a separate chute 36 being provided for each container. The side wall 33 is shown provided 35 with an upstanding flange or portion 38 which is adapted to engage the side of the chute 36, when the container 28 is in position therebeneath, so as to hold the side wall 33 in closed position while the container is being 40 filled with fuel; and this side wall 33 may also be provided with a depending extension as at 39 adapted to abut against the fire-door 15 when the latter is in closed position, thus ensuring the side wall 33 being maintained 45 in closed position.

The chute 36 may be provided with any suitable closure at its bottom, as for example a swinging door 40 suspended by links 41 arranged at each end of the chute. One of 50 the links 41 may be provided with a suitable spring as at 42 whereby the swinging door 40 is returned to and held in closed position; the door 40, at one side, being shown provided with an upstanding flange 43 on the 55 side to which the door is swung when opened; said flange limiting movement of the swinging door toward the opposite side of the chute through the action of the spring. One or both of the links 41 may be provided 60 with a suitable pull rod or cord as at 44, operable from a suitable common point to enable the operator to simultaneously open all of the chutes so that all of the containers may be filled with fuel. As soon as the pull 65 rod or cord 44 is released the swinging doors

40 of the respective chutes will move to closed position and prevent further discharge of fuel.

The pivot or journal 34 of the swinging side 32, at one end of the container, is provided with an arm 45 fixedly secured thereto and this arm, together with swinging side 32 are held in normal and returned to closed position by means of a suitable spring as at 46 which may also be secured in a suitable manner to one of the end walls of the container. The free end of the arm 45 has a cable 47 secured thereto and this cable is passed about a pulley 48 secured on the end wall of the container at a point adjacent to the opposite or forward side wall as shown in Figure 4; while the opposite end of the cable 47 is secured to a suitable drum 49 mounted on the shaft 22 on which cog-wheel 23 is secured. 75

The drum 49 is of smaller diameter and circumference than the diameter of cog-wheel 23, with the result that the cable 47 will be unwound at a slower speed than the travel of the rack-bar 24 and the container 28. As a result of this construction and arrangement, the cable 47 (which at all times is maintained taut) will cause the side 32 to be slowly swung through the container 28 while the latter is traveling at a slightly greater speed toward the inner wall of the firebox. This inward swinging movement of the wall 32 will continuously and gradually force the fuel out through the freely pivoted side 33 while the container is traveling into the firebox, and cause the fuel to be more or less evenly or uniformly distributed throughout the entire grate-bar of the firebox. 95

In operation, all of the containers 28 are initially positioned beneath their respective chutes 36 and the operator, by means of pull rods or cables 44, moves the swinging doors 40 beneath the chutes into open position thereby allowing the fuel to pass through the open tops of the containers until the latter are filled, at which time the cables 110 or pull rods 44 are released, which permits the slide doors 40, through the actions of the springs 42, to return to closed position and shut off the further discharge of fuel. The slide doors 15 of the battery of fireboxes 115 are then drawn upward through the medium of pull cords 16, at which time the motor 19 is set in operation, causing shaft 22 (which extends throughout the length of the battery of fireboxes and which is provided with a cog-wheel and a drum for each container) to be revolved. This will cause the rack-bar 120 with the container to be forced through door opening 15 toward the inner wall of the firebox. The upward movement of the slide doors 15 of the firebox, as well as the movement of the containers 28 away from their respective chutes 36, releases the swinging side wall 33 and allows it to swing into open 125 position through the action of the pressure 130

of the fuel caused by the inward movement of the side wall 32 induced by the unwinding of the cable 47 at a slower speed than the speed of travel of the rack-bar, resulting 5 from the differences in diameter of the cog-wheel and the diameter of the drum. As a result, the fuel is gradually forced out of the containers by the sweeping action of the side wall 32. Reverse movement of the 10 motor will cause the rack-bars with the containers to be withdrawn from the fireboxes and at the same time the respective cables 47 will also be wound up on their respective drums 49, so that when the containers have 15 returned to loading position beneath their respective chutes, the swinging sides 32 will have returned to closed position. In order that the swinging sides 32 cannot move outwardly, through the pressure of the fuel, 20 the container is provided with a flange as at 50 which will hold the side wall against outward movement.

I have shown what I believe to be a simple embodiment of my invention, which has been 25 described in terms employed merely as terms of description and not as terms of limitation, as structural modifications are possible and may be made without, however, departing from the spirit of my invention.

30 What I claim is:

1. A stoker, comprising a horizontally traveling member, a fuel receiving container secured to said member, the opposite sides of the container being pivoted to swing, with 25 one of said sides being adapted to swing away from the container, while the other side is adapted to swing through the container, power imparting means whereby the traveling member and the container are 40 made to move through a firebox toward the inner wall thereof, and means controlled by said power imparting means, whereby said second mentioned side of the container is moved toward the opposite side of the container.

2. A stoker, comprising a traveling member adapted to move into the firebox of a boiler, a fuel receiving container secured to said member and provided with movable 50 sides, the forward side being adapted to move outwardly into open position, while the opposite side is adapted to move into the container toward the first mentioned side, means whereby said traveling member and the container are moved into the firebox, and means, operable with said first means, whereby the second mentioned container-side is caused to move through the container while the latter is traveling through the firebox.

3. A stoker, comprising a supporting frame provided with rollers arranged in different horizontal planes, a rack-bar adapted to travel between the rollers in the different planes, a fuel receiving container secured to the forward end of said rack-bar

and having a fuel-receiving opening in its top, the opposite side wall of the container being pivotally mounted, the one side wall being adapted to swing away from the container into open position, while the second 70 side wall is adapted to swing through the container to force the fuel through the first mentioned side, a driving shaft provided with a cog-wheel and a drum of different diameters, the cog-wheel being arranged in 75 mesh with said rack-bar to actuate the latter, and a flexible element operatively connected with said second side wall and to said drum and traveling from the drum at a slower speed than the speed of the rack-bar, where- 80 by said second side wall is forced into the container while the latter is traveling into the firebox.

4. A stoker, comprising a fuel holding container provided with a fuel receiving 85 opening in the top, one side wall of the container being arranged to move outwardly, while the opposite side wall is arranged to move toward said first side wall, means whereby said second mentioned wall is yield- 90 ingly held in closed position, a horizontally traveling arm to which the container is secured, power imparting means whereby said arm with the container is caused to travel into and out of the firebox of a boiler, and means controlled by said power imparting 95 means whereby said second mentioned side wall of the container is caused to move toward the first mentioned side wall and the fuel thereby forced out of the container.

5. In a stoker of the character described, a horizontally traveling rack-bar, a fuel holding container secured to the forward end of the rack-bar, the forward side wall of the container being pivoted to swing outwardly, while the opposite or rear side wall is pivoted to swing forwardly through the container, a power shaft provided with a pinion meshing with said rack-bar, and a drum of smaller diameter than said pinion, 110 and a flexible connection between the drum and the rear side wall of the container, whereby said side wall is caused to swing forwardly while the container is traveling into the firebox and the fuel uniformly 115 forced from the container.

6. In a stoker of the character described, the combination of an overhead fuel supply chute, a container provided with an opening in its top adapted to be positioned beneath the chute, the forward side wall of the container being pivoted to swing outwardly, while the opposite or rear side wall of the container is adapted to move through the container toward said forward side wall, a 120 supporting frame, a rack-bar mounted on the frame to travel horizontally and to carry said container, a power shaft mounted in said frame and provided with a pinion meshing with the rack-bar and with a drum of 125 130

smaller diameter than the pinion, and a flexible connection between the drum and said rear side wall, said connection being so arranged that a pull on the rear side wall is exerted while the rack-bar and the container are traveling into the firebox of a boiler.

7. A stoker of the character described, comprising a supporting frame provided with a power-shaft and with rollers arranged in different horizontal planes, a bar arranged to travel horizontally between the rollers in the different planes, a fuel holding member secured to the forward end of the rack-bar, the forward side wall of the member being adapted to move outwardly while the rear side wall is adapted to move forwardly through the member, means whereby the side walls are yieldingly held in normal position, means intermediate of the power shaft and said bar whereby the latter is caused to travel horizontally, and means intermediate of the power shaft and said rear side wall of the member whereby said side

wall is caused to move forwardly while the member is traveling forwardly into the firebox of a boiler. 25

8. A stoker of the character described, comprising an overhead chute, spring controlled closure means for said chute, a fuel holding container adapted to travel horizontally toward the inner wall of a firebox, one wall of the container being adapted to move through the container toward the opposite side to force the fuel from the container, power means whereby the container is made to travel through the firebox, and means intermediate of said power means and said movable wall of the container whereby the latter is progressively moved toward the opposite side of the container while the latter is being fed into the firebox. 30 35 40
